FIG. 1.

FIG. 2.

FIG. 3.

UNITED STATES PATENT OFFICE.

HENRY F. SCHENUIT, OF PASADENA, CALIFORNIA.

ZITHER-PIANO.

1,282,636.

Specification of Letters Patent. Patented Oct. 22, 1918.

Application filed August 29, 1917. Serial No. 188,821.

To all whom it may concern:

Be it known that I, HENRY F. SCHENUIT, a citizen of the United States, residing at Pasadena, in the county of Los Angeles 5 and State of California, have invented new and useful Improvements in Zither-Pianos, of which the following is a specification.

This invention relates to a zither piano.

In the use of the ordinary piano it is 10 not difficult to obtain firm, resonant tones from the strings, due to the fact that the strings are individually struck with a positively acting hammer which insures that sufficient volume of tone will be produced 15 by the string and in proportion to the force with which the string is struck. In the construction of zither pianos it has been a matter of considerable difficulty to design a sounding board and arrange the strings 20 thereon in a manner to insure that the picking action of the string vibrating members will initially act upon the strings in a manner to cause them to produce clear tones of fine timbre. It is an object of the present 25 invention to provide a sounding board and a string arrangement thereon which will make such a result possible.

Another object of this invention is to provide a sounding board which is so constructed as to prevent buckling of the board 30 under the string tension.

Other objects will appear hereinafter.

The invention is illustrated, by way of example, in the accompanying drawings in 35 which:

Figure 1 is a plan of my sounding board as supplied with strings and suitable bridges.

Fig. 2 is a view in transverse section 40 through the sounding board as seen on the line 2-2 of Fig. 1 and as particularly illustrating the detail construction of the board.

Fig. 3 is a view in section as seen on the line 3-3 of Fig. 1 and illustrates the manner 45 in which vibration of the strings is transmitted through the frame members to the sounding board.

Referring more particularly to the drawings, 10 indicates a metallic frame adapted

to provide reinforcement for a sounding board 11. The frame 10 is substantially triangular in shape, its body portion resembling an isosceles triangle. The frame 10 as shown in Figs. 1 and 2, comprises the straight vertical web 10^a, the straight vertical web 10^b extending from the upper end of the web 10^a at an angle of about sixty degrees, the straight vertical web 10^c connecting the lower end of the web 10^a to the outer end of the web 10^b, the flanges 10^d, 10^e and 10^f extending inwardly from the webs 10^a, 10^b and 10^c slightly above their centers in cross-section, and the arm 10^g extending from the meeting ends of the webs 10^b and 10^c parallel with the web 10^a and to a point 60 in transverse alignment with the end of the web 10^a. The sounding board 11 is inserted upwardly and fits within the webs 10^a, 10^b and 10^c against the flanges 10^d, 10^e and 10^f. One of the sides of this frame is fitted 70 with a series of tuning pins 12 which are staggered in relation to each other and mounted within a wooden pin block 13 which extends along and beneath the upper edge of the sounding board. The pin block 13 is 75 inserted upwardly against the sounding board 11 in opposition to the flange 10^e, and the tuning pins 12 are inserted downwardly through large openings in the flange 10^e, through the sounding board 11, and 80 into the pin block 13. The spacing blocks 13' are inserted upwardly against the bottom of the sounding board 11 in opposition to the flanges 10^d and 10^f and match with the pin block 13. The opposite side of the 85 sounding board is provided with a series of hitch pins 14 which are fastened into the frame and positioned therealong in equally spaced relation to each other. The hitch pins 14 are rigidly mounted in the flange 90 10^e. Each of the hitch pins is opposite one of the tuning pins and thus a series of music strings 15 are stretched across the board and over a metal rib 16 adjacent the tuning pins, and a wooden bridge 17 adjacent the 95 hitch pins. The metal rib 16 extends upwardly from the flange 10^e near its inner edge and from the upper end of the flange

10^a about one-fourth of the distance to the meeting ends of the webs 10^b and 10^c for supporting the long strings only. The wooden bridge 17 extends under all the 5 strings and is located near to and parallel with the flange 10^e. It is to be noted that the wooden bridge is spaced a distance from the hitch pins. This has been done to produce a better quality of tone when the 10 strings are struck. In order to prevent the higher notes from having a metallic sound, it is preferable to position a second bridge 18 beneath the strings ranging from the second octave above middle C upwardly and 15 forming a continuation of the rib 16. This bridge is of wood and is of a height greater than that of the metallic rib 16. The wooden bridges are provided with top wires 19 and 19' which extend the length of each 20 bridge and are so mounted as to support the zither strings without permitting them to touch the wood portion of the bridge. In this manner the strings will be supported upon a narrow rib. As a means for providing 25 longer string lengths for the lower notes, the rib 16 is drawn closer to the tuning pins beneath the long strings.

Fixed beneath the frame is the sounding board 11. This board is formed of laminated strips of wood which are here shown 30 as perforated to provide sound openings 20 and 21. The opening 20 occurs between transverse metallic frame members 22 and 23, while the opening 21 is disposed between 35 the transverse member 23 and the end of the frame. By this arrangement the sound may readily pass through the sounding board and into a compartment 24 therebeneath. This compartment is inclosed by 40 means of a bottom board 25 which is formed with a series of openings 26 distributed over its surface. The bottom board 25 is inserted upwardly against the pin block 13 and the spacing blocks 13' so that its lower face is 45 substantially flush with the lower edges of the webs 10^a, 10^b and 10^c.

Reference being had to Fig. 3 of the drawings, it will be seen that the wooden bridges 17 and 18 are formed with cut-away portions 27 which accommodate the transverse ribs 22 and 23 of the frame. These ribs are not permitted to touch the bridge nor are they in contact with the sounding board for a reason which will be evident. However, at 55 the point at which the bridge passes over the ribs a sounding post 28 is positioned beneath the bridge and extends downwardly through an opening 29 in the rib and bears upon the sounding board. In this manner 60 the vibration of the strings is more effectively transmitted to the sounding board and a more pleasing tone produced.

The frame members 22 and 23 are formed integral with the flanges 10^e and 10^f and ex-

tend parallel with the web 10^a and flange 65 10^d and serve as braces between the webs 10^b and 10^c.

The leading features of the sounding board and frame thus constructed are:

The webs 10^a, 10^b and 10^c, the flanges 10^d, 70 10^e and 10^f, and the braces 22 and 23, all cast integral so as to make a rigid homogeneous frame of uniform strength and without joints;

The insertion of the sounding board 11 75 against the bottoms of the flanges 10^d, 10^e and 10^f and tightly within the webs 10^a, 10^b and 10^c;

The insertion of the pin block 13 and the spacing blocks 13' against the sounding 80 board;

The insertion of the bottom 25 against the pin block and spacing blocks;

The continuous iron band all the way 85 around the edge of the sounding board and against the upper side of the sounding board adjacent the edge.

While I have shown the preferred construction of my invention as now known to me, it will be understood that various 90 changes in the combination, construction and arrangement of parts may be made by those skilled in the art without departing from the spirit of my invention.

I claim:

1. A zither piano, comprising a continuous metal band forming a triangle, a flange 95 extending inwardly from the band intermediate of its edges, a sounding board inserted upwardly and fitting closely within the band and against the flange, spacing blocks inserted upwardly within the band against the sounding board and in opposition to the flange, and a bottom inserted upwardly against the spacing blocks. 100

2. A zither piano, comprising a continuous metal band forming a triangular frame, a flange extending inwardly from the band intermediate of its edges and all the way around, a sounding board inserted upwardly 110 and fitting closely within the band against the flange, a pin block inserted upwardly against the sounding board in opposition to the flange at one side of the triangle, spacing blocks inserted upwardly against 115 the sounding board and in opposition to the flange at the other two sides of the triangle, hitch pins fixed in the flange at one side of the triangle, bridges mounted upon the sounding board, strings attached to the pins and extending over the bridges, and tuning pins inserted downwardly through loose openings in the flange into the pin block, the other ends of the strings being attached to the tuning pins. 120

3. A zither piano, comprising a vertical web forming a continuous triangular wall, a continuous flange extending inwardly from

the web intermediate of its edges, and braces extending across the opening in the frame and parallel with one side.

4. A zither piano, comprising a continuous metal web forming a triangular frame, a continuous flange extending inwardly from the web intermediate of its edges, a sounding board inserted upwardly and fit-

ting within the web against the flange, spacing blocks inserted upwardly against the sounding board, and a perforated bottom board inserted upwardly against the spacing blocks.

In testimony whereof I have signed my name to this specification.

HENRY F. SCHENUIT.
